V. H. EMERSON

PHONOGRAPH BLANK

Filed Oct. 16, 1919

FIG. 1.

FIG. 2.

Inventor
Victor H. Emerson

By his Attorney

W. Day Emerson

UNITED STATES PATENT OFFICE.

VICTOR H. EMERSON, OF NEW YORK, N. Y., ASSIGNOR, BY MESNE ASSIGNMENTS, TO METAL RECORDING DISC COMPANY, INC., A CORPORATION OF NEW YORK.

PHONOGRAM BLANK.

Application filed October 16, 1919. Serial No. 331,147.

To all whom it may concern:

Be it known that I, VICTOR H. EMERSON, a citizen of the United States, residing at the city, county, and State of New York, 5 have invented new and useful Improvements in Phonogram Blanks, of which the following is a specification.

My invention relates to apparatus for producing sound records, and has for an object the production of a blank that may be employed in forming a record groove adapted to receive undulations upon its upper edges only.

I have in a co-pending application, Serial 15 No. 331,146, disclosed a process for forming in the top edges of a non-undulatory groove sound undulations by means of an ordinary phonograph reproducing device, and also for a record, the product of my 20 said process.

While the record of my co-pending application may be produced by a process employing a simple form of groove, it is found highly advantageous to trace the record 25 formed therein if the surfaces adjacent the groove be slightly raised so as to minimize the mass of material to be indented in forming the type of groove hereinabove described, namely, having its undulatory walls thus 30 limited to the upper surfaces of the groove.

Therefore my present invention, described in general terms, comprises a blank for making original sound records having a groove formed with upturned lips at either side 35 thereof.

The accompanying drawings illustrate a preferred form of my invention, of which—

Figure 1 is a plan view of a blank of 40 my invention for producing a disk sound record having the non-undulatory spiral record shown in the surface thereof; and

Fig. 2 is an enlarged fragmentary sectional view showing in perspective a preferred non-undulatory groove of my invention.

Referring to the drawings, the numeral 1 represents a disk preferably made of a suitable metal for recording therein sound waves, such as copper or other metal having a comparatively soft metallic body for receiving and retaining undulations made by a relatively blunt or rounded tracing point.

Zinc and lead may be employed with good results as the body material of my improved

blank, yet I find copper in many respects 55 superior to other metallic substances and use it in preference generally over all other materials.

The groove 2 conforms to a plain spiral sunk into the flat surface of the disk 1 which 60 may have any convenient form as determined by the shape of the cutting or tracing tool with which it may be formed, providing that the top portions 3 of each side wall shall be approximately vertical and extend 65 upwardly beyond the plane of the disk blank so as to form the sharp-edged lip 5 with the surface 4, inclined at approximately 45 degrees to the surface 3.

The lip 5 is formed upon both sides of 70 the groove of substantially equal height and size and is relatively narrow as compared with the width of the groove itself. That is to say, the groove proper may have greater or less depth as may suit other requirements, 75 but the size and shape of the ridges 5 at respective sides must not only be equal and oppositely disposed but will equal in height and width the average depth or amplitude of the sound undulations to be recorded 80 therein.

Thus in Fig. 2 of the drawing a relatively wide and deep groove is shown, while the fin-like edges are adapted to receive undulations along the top portion of the groove, 85 leaving the bottom free for other uses or purposes, such for example as the segregation of dust particles and foreign matter that interfere with ideal phonographic reproduction.

The angular pointed edge 5, if made in copper, for example, will, because of its narrow body, receive to the full depth of its vibrations the indentations of a blunt tracing point for recording the sound waves 95 therein; and furthermore by maintaining the declivity of substantially 45 degrees for the inclined surfaces 4 the height of the edge 5 may be varied without fundamentally altering the adaptability to receive the wave undulations for which it is designed.

The purpose of my disk blank is to provide a blank that may be employed in connection with an ordinary phonograph for recording sound waves thereon. This is accomplished by inserting in the sound box 100 a tracing ball or similar reproducing point of greater diametral width than the dis-

tance separating the lips 5 of the respective grooves and then placing the disk blank 1 upon the turntable of the phonograph.

The weight of the sound box will carry 3 the ball tracing point of the phonograph down into the material sufficiently in case of recording laterally so as to insure its embedding itself into first one and then the other ridges 5 at the two sides of the groove 10 2, which in turn will act as a guiding means to retain the ball point in the groove from one end to the other.

Having described my invention, what I claim is:

15 1. A blank for original sound records having a non-undulatory groove with similar upturned edges at its sides.

2. A blank for recording sound waves with a spiral groove having side walls sub-

stantially vertical at their tops, and extending above the surface of the blank and inclined surfaces converging with said extended vertical walls.

3. In a blank for original sound records a spiral groove having angular ridges at its 25 respective sides, said ridges comprising vertical walls coincident with the sides of the groove and angular surfaces disposed at substantially 45 degrees to said walls.

4. In a blank for original sound records 30 a groove having vertically projecting lips at its respective sides, said lips having angular edges whose surfaces are disposed at substantially 45 degrees.

In testimony whereof I have hereunto set 35 my hand.

VICTOR H. EMERSON.
